Patented Jan. 5, 1926.

UNITED STATES PATENT OFFICE.

THOMAS S. NOGUCHI, OF NEW YORK, N. Y.

CLEANING COMPOUND.

No Drawing.

Application filed September 22, 1924. Serial No. 739,208.

To all whom it may concern:

Be it known that I, THOMAS S. NOGUCHI, a subject of the Emperor of Japan, and a resident of the city of New York, borough 5 of Manhattan, in the county and State of New York, have invented a new and Improved Cleaning Compound, of which the following is a full, clear, and exact description.

10 The present invention relates to new and useful improvements in cleaning compounds, and it pertains more particularly to a compound especially adapted for use in cleaning and polishing furniture, automobile bodies, or any other article having a finished surface.

It is one of the primary objects of the invention to provide a cleaning compound which will have a cleaning and polishing 20 effect upon surfaces to which it is applied.

It is another object of the invention to provide a cleaning compound which will have oil-exuding characteristics without the necessity of supplying oil thereto from time 25 to time.

It is a further object of the invention to provide a means for checking the exudation of oil for the purpose of preventing a greasy or oily compound.

30 In carrying out the invention shelled peanuts are finely ground and are combined with camphor, preferably in flake form, any type of camphor being suitable for the purpose.

35 In making up the compound the propor-

tions are two pounds of ground peanuts to one pound of camphor, as, for example; two pounds of ground peanuts with one pound of flaked camphor, and the same thoroughly mixed.

40 This compound is preferably placed within a bag and the oil exuded by the ground peanuts is absorbed by the material forming the bag, and when the bag is rubbed in contact with a surface, the surface will take 45 on a cleaned and polished appearance.

The camphor checks the exudation of oil from the ground peanuts to the extent that the bag in which the cleaning compound is contained never becomes greasy or wet from 50 the oil exuded by the peanuts, but is always of the proper degree of dampness to give a cleaning and polishing effect to the surface with which it is rubbed in contact.

55 What is claimed is:

1. A cleaning and polishing compound comprising ground shelled peanuts combined with camphor, in the proportions of two parts of ground shelled peanuts to one 60 of camphor.

2. A cleaning and polishing compound comprising ground shelled peanuts combined with camphor in the proportions of two parts of ground shelled peanuts to one 65 part of camphor, the camphor being in flaked form.

3. A composition of matter comprising ground peanuts combined with camphor.

THOMAS S. NOGUCHI.
